Primary Examiner — Catherine Ho*Assistant Examiner* — Natalya M Rapundalo(74) *Attorney, Agent, or Firm* — Foundation Law Group LLP; Sevag Demirjian; J D Harriman(57) **CLAIM**

We claim the ornamental design for a bottle holder, as shown and described.

DESCRIPTION

FIG. 1 is a top, front, left side perspective view, showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is a side perspective view.

The broken lines in FIG. 7 represent portions of the bottle holder and form no part of the claimed design. The broken lines in FIG. 8 represent environment and form no part of the claimed design.

1 Claim, 8 Drawing Sheets(56)
